(57) CLAIM

The ornamental design for a deck light, as shown and described.

DESCRIPTION

FIG. 1 is a top plan view of a deck light in accordance with the present invention;

FIG. 2 is a left side view of the deck light of FIG. 1;

FIG. 3 is a front view of the deck light of FIG. 1;

FIG. 4 is a right side view of the deck light of FIG. 1;

FIG. 5 is a rear view of the deck light of FIG. 1;

FIG. 6 is a bottom plan view of the deck light of FIG. 1, on a reduced scale; and,

FIG. 7 is a perspective view of the deck light in accordance with the present invention.

The broken lines in FIGS. 2, 3, 4, 5 and 6 are for illustrative purposes only and form no part of the claimed design.
